TOM-TOM DRUM CASE OR THE LIKE

Alfonso D. Samperi, 6853 Suva St.,
Bell Gardens, Calif. 90201

Filed Sept. 7, 1966, Ser. No. 3,763

Term of patent 14 years

(Cl. D56—1)

FIG. 1.

FIG. 4.

FIG. 2.

FIG. 5.

FIG. 3.

FIGURE 1 is a perspective view of the tom-tom drum case or the like showing my new design.

FIGURE 2 is a top plan view thereof.

FIGURE 3 is a front elevational view thereof.

FIGURE 4 is a rear elevational view thereof.

FIGURE 5 is a side elevational view thereof.

The essential features of my design reside in the portions shown in solid lines, the conventional legs being shown in broken lines.

I claim:

The ornamental design for a tom-tom drum case or the like, substantially as shown and described.
